UNITED STATES PATENT OFFICE.

FREDERICK W. FRENCH, OF OAKLAND, CALIFORNIA.

VERTICAL FILE.

Application filed September 15, 1927. Serial No. 219,696.

This invention has reference to filing cabinets and aims to provide means to be installed in the usual drawers of a filing cabinet so that the space within a drawer may be divided into compartments so that filing may be accomplished with facility.

An important object of the invention is to provide a device of this character which is adjustable and may be used in connection with boxes or drawers of various sizes within certain limits.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed, without departing from the spirit of the invention.

Referring to the drawings:

Figure 1 is a side elevational view illustrating a drawer equipped with a device constructed in accordance with the invention; Figure 2 is a front elevational view of the drawer; Figure 3 is a rear elevation of the drawer; Figure 4 is a fragmental horizontal sectional view on line 4—4, Fig. 1; Figure 5 is a section on line 5—5, Fig. 1; Figure 6 is a fragmental perspective view of the device; Figure 7 is a front elevational view of a modified form of drawer; Figure 8 is a side elevational view thereof, partly in section; and Figure 9 is a section taken on line 9—9 of Figure 8.

Referring to the drawings in detail, the reference character 5 designates the drawer of a filing cabinet which is provided with two pairs or sets of openings 6 arranged in its rear end wall, the openings 6 of each pair being disposed in vertical spaced relation for purposes to be hereinafter more fully described.

The metallic drawer being constructed in the usual and well known manner includes a front end wall 7 and an inner end wall 8 spaced therefrom, the inner wall 8 being provided with openings 9. Disposed at opposite sides of the drawer are supporting rods 10 that are formed with corrugations throughout their lengths defining irregularities to hold the cross bars 11 of the pockets against accidental displacement. The inner ends of the rods 10 are bent at right angles as at 12, the right-angled ends having lateral ex-

tremities 13 to be fitted in the openings 6 to secure the inner ends of the rods within the drawer. Ears indicated at 14 are stamped from the inner end wall of the drawer and are extended inwardly, the ears being arranged in suitable spaced relation with the sides of the drawer to permit the right-angled ends 12 of the rods to be positioned between the ears and sides of the walls.

The forward ends of the rods 10 extend upwardly as at 15 and are designed to be positioned in the openings 9 of the wall 8 to lock the forward ends of the rods within the drawer. A transversely disposed rod 16 is positioned at the forward end of the drawer and is provided with reduced end portions fitted in openings formed in the sides of the drawer. This rod 16 acts as a support for the forward end of the flexible material of which the pockets are formed. The side members of the drawer are also provided with openings spaced from the openings in which the reduced ends of the rod 16 are disposed, so that when the rods 10 are moved to their lowermost positions, the ends of the rod 16 may be positioned in the last-mentioned openings.

Forming an important feature of the invention are the pockets which are indicated generally by the reference character 17, the pockets being formed of suitable flexible material that hang into the drawer, the upper edges thereof being connected with the cross bars 11 for supporting the pockets, the front end of the first pocket being connected to the rod 16.

As shown, these bars 11 are formed with notches 18 extended from the lower edges thereof, upwardly and laterally defining hooks 19 that may be hooked over the rods 10 to support the pockets and permit the pockets to be slid longitudinally of the rods 10 to the end that the pockets may be moved into close engagement with each other when the drawer is to be closed or the bars 11 may be separated to permit of easy access to the cards supported therein.

In order that the bars 11 will be held against movement over the rear ends of the rods 10, lugs 20 are formed at the inner ends of the rods, which lugs act as stops to limit the movement of the bars 11.

When the device is to be used in connection with filing cabinets embodying wooden drawers, openings such as indicated at 21 are provided in the front wall 22 of the drawer,

which openings accommodate the forward ends of the rods 23.

The rear ends of the rods 23 are also positioned in openings 24 that are arranged in the rear end wall of the drawer. In this form of the invention it is to be understood that pockets similar to those previously described, are supported by the rods 23 and are operated in the same manner as the pockets previously described.

From the foregoing it will be seen that due to the construction shown and described, the usual filing cabinet drawer will be readily and easily converted into a drawer having numerous compartments for the reception of cards employed in filing.

I claim:

1. In combination with a filing cabinet drawer having sets of vertically spaced openings in the front and rear end walls thereof, rods having their ends positioned within the openings so as to be adjustable, said rods having irregular portions, partitioning members, and means on the partitioning members for engaging the irregular portions to hold the partitioning members in various positions of adjustment.

2. In a filing cabinet drawer having a rear wall formed with openings, an inner wall dis-

posed adjacent to the front of the drawer 30 and having openings, supporting rods having their rear ends disposed in the openings of the end wall, the forward ends of the rods being positioned in the openings of said inner wall, a rod extending across the drawer 35 and contacting with the supporting rods at the front ends thereof, and means movable longitudinally of the supporting rods for supporting articles.

3. A filing cabinet drawer including side 40 walls and front and rear end walls, said rear wall having vertically spaced openings formed therein, ears extending inwardly from the rear wall, an inner end wall spaced from the front wall and having vertically 45 spaced openings, supporting rods having one of their respective ends disposed in certain of the openings of the end wall, said ears engaging the rods to hold the rods against lateral movement, the opposite ends of said supporting rods extending into corresponding openings of the inner end wall, and means on the rods for supporting articles held in the drawer.

In testimony that I claim the foregoing as 50 my own, I have hereto affixed my signature

FREDERICK W. FRENCH.
